COMBINED SADDLE AND OILER FOR UPPER
DRAFT ROLLERS OF SPINNING FRAMES

Floyd Aldridge, Belmont, N. C.

Application February 17, 1948, Serial No. 8,834

2 Claims. (Cl. 19—138)

1

My invention relates to spinning frames, and more particularly to a combined saddle and oiler for the draft rollers of spinning frames.

A primary object of the invention is to provide a combined saddle and oiler for the upper draft rollers of spinning frames, which will more effectively provide the necessary lubrication, without the use of any wicks.

A further object is to provide a combined saddle and oiler, wherein the lubricating oil is entirely enclosed within the oiler prior to its application upon the roller, and therefore cannot run over the machinery or yarn.

A further object is to provide a saddle and oiler which will effect a saving of oil and yarn, which are wasted with present types of oilers.

A further object is to provide an oiler which meters the oil directly and evenly upon the upper draft rollers at the point where it is needed for lubrication.

A still further object of the invention is to provide a combined saddle and oiler which is simple, practical, and inexpensive to manufacture.

Other objects and advantages of the invention will be apparent during the course of the following description.

In the accompanying drawings, forming a part of this application, and in which like numerals are employed to designate like parts throughout the same,

Figure 1 is a central vertical longitudinal section through the combined saddle and oiler, and showing the same applied to the upper draft rollers of a spinning frame.

Figure 2 is a plan view of the device as shown in Figure 1, parts omitted, and parts broken away.

In the drawings, where for the purpose of illustration is shown a preferred embodiment of the invention, the numeral 5 designates generally a single set or stand of draft rollers of a conventional type of spinning frame. This stand 5 of draft rollers comprises lower draft rollers 6, and the usual upper draft rollers 7, which are mounted upon a suitable frame 8, and adapted to be moved vertically into and out of contact with the lower rollers 6. The lower and upper draft rollers 6 and 7 are cylindrical, and the yarn is drawn between the contacting cylindrical surfaces, as is well known.

The upper rollers 7 are maintained in engagement upon the lower rollers 6 by means of a combined saddle and oiler 9, which is held down in the usual manner by an adjustable generally vertical stirrup 10, which is pivotally connected to a generally horizontal lever 11, pivoted to the

2

spinning frame as at 12. The free end of the lever 11 carries a weight 13, which provides the necessary downward pull upon the saddle and oiler 9. The combined saddle and oiler is thus held in frictional engagement against the rotating upper draft rollers 7.

I will now describe in detail the combined saddle and oiler 9 which embodies the present invention. The combined saddle and oiler 9 comprises a unitary elongated body or chamber 14, provided with a main longitudinally extending channel or bore 15. The body 14 is formed of metal, and may have any desired shape in transverse cross section, such as rectangular. The main bore 15 is formed in the upper end 16 of the body 14, and the bore 15 terminates short of the opposite end 17, forming a trap or chamber for the lubricating oil. A suitable lubricating oil cup or reservoir 18 is mounted upon the end 16 of body 14. This oil cup 18 includes a bottom lateral inclined discharge stem or nipple 19, which is screw threaded, and engages in an end screw threaded portion 20 of the main bore 15. Oil in the cup 18 is gravity fed into the bore 15. The oil cup 18 has a pivoted cover or cap 21, to keep foreign matter out of the oil. Formed upon the bottom of the body 14 are a pair of parallel spaced depending lugs or projections 22, which are adapted to straddle the uppermost roller 7, as shown. The lugs 22 serve to position the combined saddle and oiler 9 with respect to the upper rollers 7 and to hold it against longitudinal movement. The uppermost roller 7 is of course freely rotatable between the lugs 22.

Near each of the upper draft rollers 7 the body 14 is provided with bottom lateral conically tapered ports or oil discharge openings 23, 24, and 25. These tapered ports 23, 24, and 25 lead into the main bore 15, as shown. The tapered port 23 is disposed at the point where the bottom side of body 14 engages the adjacent roller 7, and the port 23 is adapted to supply oil directly upon the roller 7. All of the upper draft rollers 7 have grooves 26 formed in their cylindrical surfaces and near their longitudinal centers. The combined saddle and oiler 9 engages the rollers 7 at these grooves 26 and the lubricating oil is applied only to the surface of the grooves 26. Adjacent the center roller 7, a small depending projection or boss 27 is formed upon the bottom of the body 14, and this boss 27 has a transverse cylindrically curved recess 28, which bears against the surface of groove 26. The boss 27 is provided with a small port 29, which leads to the tapered port 24. Adjacent to the lowermost

roller 7, the body 14 has formed upon it a depending boss 30, provided with a transverse cylindrically curved recess 31, which bears upon the groove 26 of adjacent roller 7. A short bottom longitudinal groove 32 is formed in the bottom surface of boss 30 and leads into recess 31 from a countersunk port 33, which leads to the tapered bore 25.

Opposite each of the tapered ports 23, 24, and 25, the body 14 is provided with transverse screw threaded openings 34, which receive screw threaded valve elements 35, having conically tapered valves 36 to enter the ports 23, 24, and 25. The valve elements 35 are held in their selected adjusted positions by nuts 37, seated upon washers 38, as shown. The valves 36 are adjusted with respect to the ports 23, 24 and 25, so that the desired quantity of oil will be applied to the rollers 7 by the combined saddle and oiler.

Formed upon the top side of body 14, near the center opening 34, is an upstanding boss 39, having a longitudinal screw threaded opening 40, to receive a stirrup adjusting screw 41. The head 42 of the adjusting screw 41 has an annular groove 43 formed in it, to receive the top of the stirrup 10, as shown.

In use, the combined saddle and oiler 9 serve to clamp the upper draft rollers 7 against the lower rollers 6, as stated. This creates considerable friction between the upper rollers 7 and the combined saddle and oiler. Therefore, the combined saddle and oiler is designed to apply oil to the grooves 26 of rollers 7, as explained. It is thought that the chief advantages of the combined saddle and oiler herein described, are set forth in the foregoing objects of the invention.

It is to be understood that the form of the invention, herewith shown and described is to be taken as a preferred example of the same, and that various changes in the shape, size and arrangement of parts may be resorted to, without departing from the spirit of the invention, or the scope of the subjoined claims.

Having thus described the invention, I claim:

1. The combination with upper draft rollers of a spinning frame, said rollers having transverse peripheral grooves intermediate their ends, of a combined saddle and oiler mounted within the grooves of said draft rollers, said saddle and oiler comprising a body positioned longitudinally of said upper draft rollers and supported in the peripheral grooves of the latter, said body having a longitudinal bore extending inwardly from one end and terminating at a point adjacent to and spaced from the other end of said body, there being a plurality of longitudinally spaced ports extending transversely through one wall of said body, each of said ports having one end in communication with the bore of said body and having the other end in communication with the groove 60

5 of the adjacent roller, a plurality of valve elements positioned transversely of and rotatably supported in said body for movement toward and away from said ports and each having one end in alignment with one of said ports and having the other end projecting beyond said body, hand actuatable means on each of the projecting ends of said valve elements for securing said elements in any selected position of rotational movement, an oil supply positioned adjacent said one end of said bore, and a conduit having one end connected to said oil supply and having the other end connected to said one end of said bore.

2. The combination with upper draft rollers of a spinning frame, said rollers having transverse peripheral grooves intermediate their ends, of a combined saddle and oiler mounted within the grooves of said draft rollers, said saddle and oiler comprising a body positioned longitudinally of said upper draft rollers and supported in the peripheral grooves of the latter, said body having a longitudinal bore extending inwardly from one end and terminating at a point adjacent to and spaced from the other end of said body, there being a plurality of longitudinally spaced ports extending transversely through one wall of said body, each of said ports having one end in communication with the bore of said body and having the other end in communication with the groove of the adjacent roller, a plurality of threaded valve elements positioned transversely of and in threaded engagement with said body for movement toward and away from said ports and each having one end pointed and in alignment with one of said ports and having the other end projecting beyond said body, hand actuatable means on each of the projecting ends of said valve elements for securing said elements in any selected position of rotational movement, an oil supply positioned adjacent said one end of said bore, and a conduit having one end connected to said oil supply and having the other end connected to said one end of said bore.
